UNITED STATES PATENT OFFICE.

ALEXANDER STROBL, OF NEW YORK, N. Y., ASSIGNOR TO S. STERNAU & COMPANY, INC.,
A CORPORATION OF NEW YORK.

SOLID-ALCOHOL BURNER.

1,267,475.

Specification of Letters Patent. Patented May 28, 1918.

Application filed January 19, 1915. Serial No. 3,022.

To all whom it may concern:

Be it known that I, ALEXANDER STROBL, a subject of the King of Hungary, and a resident of the borough of Manhattan, city, 5 county, and State of New York, have invented a certain new and useful Solid-Alcohol Burner, of which the following is a specification.

This invention relates to burners or to devices for burning solid hydrocarbon fuel, such as solid alcohol. In an application for patent filed by me, February 11, 1915, Serial 10 No. 7503, I describe one form of solid alcohol which can be utilized in the burner forming the subject matter of this application.

The objects of the invention are

First: To produce a burner which will have improved efficiency.

Second: To reduce the period of time necessary, after the fuel is ignited, to cause the burner to give off the maximum amount of heat.

These and further objects will more fully appear from the following specification and 25 accompanying drawings, considered together or separately.

The drawings illustrate one embodiment of the invention.

Figure 1 is a top view of the burner;

30 Fig. 2 is a section on the line 2—2 of Fig. 1 with the cover or cap removed;

Fig. 3 is a similar view showing the cap in place; and

35 Figs. 4 and 5 are detail views of modifications.

In all views, like parts are designated by the same reference characters.

According to the embodiment chosen for illustration, there is a receptacle 1. This receptacle is shown as of cylindrical shape, closed on the sides and bottom. Within the receptacle is a solid hydrocarbon fuel 2. Associated with the receptacle is a chimney 3. This chimney is vertically arranged, 45 preferably over the center of the receptacle. It preferably extends down into the receptacle. The purpose of the chimney is to create a draft in the ascending burning products of combustion. I prefer to make the 50 chimney conical, as shown, which will have the effect of converging the flame. It will also have, to some extent, the function of increasing the velocity of the escaping hot products of combustion so that the efficiency 55 of the burner is increased. Associated with

the chimney is an annular opening 4 for admitting air to the interior of the receptacle. I have illustrated this opening as outside of the chimney as the best and most efficient arrangement. This annular opening is defined 60 on its inner side by the chimney 3. Its outer edge is defined by a wall 5. This wall is shown as separate from the side of the receptacle. In order to suspend the chimney suitable devices are employed, those illustrated comprising supports 6, 6, connecting the wall 5 and chimney. Outside of the wall 5 is shown an annulus 7 connecting the wall to the receptacle. The width of this annulus may be made as wide as desired. For the 65 purpose of preventing evaporation of the volatile constituents of the hydrocarbon when the burner is not in use, I employ the cover 8, see Fig. 3. This cover as shown, has a reentrant lower edge ending in a flange 70 and makes a close fit with the wall 5. When the cover is in place the chimney 3 and annular opening 4 are inclosed.

The fuel is introduced into the receptacle, and there is nothing in the receptacle above 80 the top of the fuel. The interior of the receptacle therefore contains no wicks or screens necessary to burn liquid fuel, but on the contrary the interior of the receptacle above the fuel and below the chimney is entirely unencumbered.

In operation, upon the hydrocarbon being ignited, the products of combustion will pass upward through the chimney 3 and air will be drawn down through the annular opening 4. This air will support combustion inside of the receptacle. The air will enter the receptacle in the form of a cylindrical column. The velocity of the inrushing air will carry the flame to the surface of the fuel. The flame therefore will be in close contact with the fuel throughout the entire surface of the latter. For this reason the fuel will very quickly melt and the volatile hydrocarbons which produce combustion will be more rapidly given off. The burner therefore will not only produce an efficient and more intense flame after it has been burning for some time, but it will be brought to its maximum efficiency very rapidly. This rapidity, 95 of reaching its maximum efficiency, is increased by the flame being supported on the surface of the liquid where heat will be radiated and raise the temperature of the side walls of the receptacle. The radiant 100

105

110

heat from the flame is thereby transmitted through the material of the walls, which are preferably metal, to the fuel and assists in the more rapidly melting of the latter. I find that the combustion is very perfect and that carbon is not deposited upon receptacles heated by the burner as freely as is the case where my improvement is not employed. As the fuel is consumed its surface is lowered and nevertheless the flame will always be in close contact with that surface. This will last until all the fuel is consumed.

In Figs. 1, 2 and 3 I have shown the chimney 3 as being permanently attached to the receptacle 1 to form a unitary structure.

Fig. 4 shows the receptacle 1 as having its mouth as large as its greatest diameter and the chimney 3^a is supported by an annulus 7^a and a bead 9. When placed on the market the can is closed by an ordinary friction or other cover. When it is desired to use the burner the cover is removed and the chimney 3^a is inserted in its place. When it is desired to extinguish the flame a cap similar to that shown in Fig. 3 is placed in position over the chimney to engage the wall 5^a and as the annulus 7^a makes an air tight joint with the can it will be hermetically sealed.

In Fig. 5 is shown a casing 10 in which the receptacle is placed after its cover has been removed. The casing is provided at its upper edge with screw-threads 11 and the chimney 3^b is provided with a depending flange similarly threaded which will engage the first mentioned threads. The chimney 3^b may have a cap like that shown in Fig. 3. The can shown in Fig. 5 is provided with an annulus 7^b and a depending wall 5^b for the reception of an air tight cover.

It will be seen that the chimneys shown in Figs. 4 and 5 may be sold separately from the receptacle and one chimney may be used on any number of burners.

With the receptacle shown in Fig. 4 it will be possible, on account of its unrestricted mouth, to recharge the can by inserting a charge of solid alcohol having the same size of the can.

The chimney shown in Fig. 4 may be applied directly to the can shown in Fig. 5 by engagement of the wall 5^a of the chimney with the wall 5^b of the can.

It is obvious that various modifications may be made without departing from the spirit or scope of my invention.

In addition to the apparatus above described, my invention also comprises the novel method by means of which the solid hydrocarbon is burned in an inclosed vessel.

In accordance with the provisions of the patent statutes, I have described the principle of my invention, together with the apparatus which I now consider to repre-

sent the best embodiment thereof; but I desire to have it understood that the apparatus shown is merely illustrative and that the invention may be carried out in other ways.

Having now described my invention, what I claim as new and desire to secure by Letters Patent is:

1. A burner comprising a receptacle open at the top, a solid hydrocarbon fuel within the receptacle, a chimney associated with the opening and of less diameter than the opening, providing an annular orifice outside of the chimney, said orifice directing the air to support combustion on the entire exposed surface of the fuel, the inside of the receptacle being unencumbered above the top of the fuel and below the chimney.

2. A burner comprising a receptacle open at the top, a solid hydrocarbon fuel within the receptacle, a chimney associated with the opening and of less diameter than the opening, said chimney being conical in shape and of less diameter at the top than at the bottom, a wall concentric to the chimney and outside thereof, producing an annular opening between the chimney and the wall, the inside of the receptacle being unencumbered above the top of the fuel and below the chimney and wall whereby combustion will be supported on the entire exposed surface of the fuel.

3. A burner comprising a receptacle open at the top, an annulus at the top, a solid hydrocarbon fuel within the receptacle, a depending wall supported by the annulus, a chimney concentric with the wall, supports for the chimney carried by the wall, said wall and chimney producing an annular opening concentric to the chimney, the interior of the receptacle being entirely unencumbered above the top of the fuel and below the chimney and wall whereby the air will be directed to support combustion on the entire exposed surface of the fuel irrespective of the level of the fuel.

4. A burner comprising a receptacle open at the top, a solid hydrocarbon fuel within the receptacle, a removable chimney associated with the opening and of less diameter than the opening, providing an annular orifice outside of the chimney, said orifice directing the air to support combustion on the entire exposed surface of the fuel, the inside of the receptacle being unencumbered above the top of the fuel and below the chimney.

5. A burner comprising a receptacle open at the top, a solid hydrocarbon fuel within the receptacle, a chimney supported within the opening and of less diameter than the opening, providing an annular orifice outside of the chimney, said orifice directing the air to support combustion on the entire exposed surface of the fuel, the inside of the

receptacle being unencumbered above the top of the fuel and below the chimney.

6. A burner comprising a receptacle open at the top, a solid hydrocarbon fuel within 5 the receptacle, a removable chimney supported within the opening and of less diameter than the opening, providing an annular orifice outside of the chimney, said orifice directing the air to support combustion on 10 the entire exposed surface of the fuel, the

inside of the receptacle being unencumbered above the top of the fuel and below the chimney.

This specification signed and witnessed this ninth day of January, 1915.

ALEXANDER STROBL.
